INVENTORS

UNITED STATES PATENT OFFICE

HARRY E. LEETY AND JOHN A. ECKERT, OF PITTSBURGH, AND AUSTIN W. PAGE, OF PENN TOWNSHIP, ALLEGHENY COUNTY, PENNSYLVANIA, ASSIGNORS TO P. WALL MANUFACTURING SUPPLY COMPANY, OF PITTSBURGH, PENNSYLVANIA, A CORPORATION OF PENNSYLVANIA

FURNACE

Application filed August 8, 1925. Serial No. 48,978.

The present invention relates broadly to liquid and gaseous fuel burners, and more particularly to burners of this type, such as usually referred to as "blow torches" or "furnaces", and especially adapted to the use of linemen, plumbers and the like, where portable heating units are required, although the utility of the invention is not limited in this respect.

10 For the sake of convenience in description, such units will hereinafter be referred to as "furnaces", it being understood that the term is used generically as definitive broadly of a general type of apparatus.

15 In furnaces of this character as now constructed, there is a fuel reservoir usually forming the base of the furnace, a burner projecting therefrom and fed thereby, a supporting top for the pot or other article to be heated, and a carrying bail or handle. It is desirable to provide such furnaces with a guard to protect the flame from undue wind currents, but such guard must be of a construction permitting ready access to the operating parts of the burner, and one of the objects of the invention is to provide an improved guard for this purpose.

It is also usually necessary with such furnaces to provide a fuel-collecting cup for the reception of a priming charge effective for preliminarily heating the burner to obtain the required vaporization of the fuel. The workmen using the furnaces ordinarily fill such cups to the top and when the fuel is heated, the resulting expansion and boiling frequently causes lighted fuel to fall on the top of the reservoir. This is decidedly objectionable as not infrequently the temperature within the reservoir becomes high enough to produce spontaneous combustion therein, which while not always rupturing the reservoir, at least distorts and weakens it, thereby rendering its continued use extremely dangerous. In other cases, spontaneous combustion may be produced by the burning of an accumulation of foreign matter on the reservoir, such for example, as paraffin, wax, pitch, dust or other substances.

The present invention has for further of its objects a guard construction that will not

add any difficulties from the standpoint of cleaning of the top of the reservoir should any objectionable matter by any chance reach the same, and also the provision of a shield or deflector between the cup and reservoir 55 adapted to prevent burning fuel or any foreign matter from dropping on to the reservoir, while at the same time, shielding the reservoir from radiated heat.

Other objects of the invention are to provide improved structural features with respect to the general guard construction and mounting, the cup and shield construction, the valve for controlling the supply of fuel to the burner, the pressure pump and safety features effective under certain heat conditions for automatically relieving pressure conditions within the reservoir.

In the accompanying drawings, there are shown for purposes of illustration only, certain preferred embodiments of the invention, it being understood that the drawings do not define the limits of our invention as changes may be made in the construction and operation disclosed therein, without departing from the spirit of the invention or the scope of the broader claims.

In the drawings:

Figure 1 is a vertical sectional view through one form of furnace embodying the present invention, certain of the parts being shown in elevation or partly broken away for the sake of clearness;

Figure 2 is a front elevation of the furnace shown in Figure 1, the filler plug being 85 partly broken away;

Figure 3 is a transverse sectional view on the line III—III of Figure 1, looking in the direction of the arrow;

Figure 4 is a detail sectional view on an enlarged scale illustrating an improved construction for the controlling valve;

Figure 5 is a detail sectional view on an enlarged scale on the line V—V of Figure 3;

Figure 6 is a detail sectional view on an enlarged scale, illustrating a modification of the present invention;

Figure 7 is a detail view illustrating still another form of the invention.

In accordance with the present invention,

there may be provided a furnace having a reservoir 2, adapted to contain a predetermined supply of fuel and forming a base for the entire furnace. This reservoir preferably has the main body thereof shaped from a single blank of metal to eliminate the necessity for providing seams in the main body and is formed with a separate bottom 3, spaced above the plane of the lower edge 4, 10 to provide a wearing surface without endangering the strength of the reservoir.

The upper wall 5 of the reservoir is preferably crowned, as clearly shown in Figure 1, to provide a downwardly and outwardly extending deflecting surface from which adhering particles may be quickly brushed. Extending upwardly from this upper wall is a cylindrical sheet metal guard 6, preferably having a hinged connection 7, 15 directly with the reservoir whereby the lower edge 6^a of the guard may bear directly against the reservoir, without the necessity of providing an intermediate shoulder or band, such as would serve to retain and permit an accumulation of foreign particles on 20 the top wall of the reservoir. It will be understood that this guard may be swung bodily at will about its pivotal mounting, it being conveniently held in operative position by a suitable clamping or latching means of any desired type or design, wing nuts 8 being shown in detail in Figure 5 for purposes of illustration only.

Carried by the guard 6 is a top plate 9, 35 which may conveniently be provided with a flange 10, for the reception of a secondary guard 11 for the melting pot or other article mounted on the plate. The guard plate may be provided with stepped supports to center 40 a pot, and cooperate with pots of different sizes to prevent slipping or tilting.

Projecting downwardly into the reservoir is a fuel-feeding tube 12, preferably threaded at its upper end into a combined nut and valve 13, illustrated in detail in Figure 4. This nut and valve body may, in turn, be threaded on to a bushing 14, suitably carried by the reservoir, and preferably brazed in position therein to provide a liquid-tight 50 connection. The combined nut and valve body 13 has a port 15 communicating with the fuel supply pipe 12, and a secondary port 16, communicating with the lower end of a burner tube 17 threaded therein. The ports 55 15 and 16 are conveniently connected by a laterally extending passage 18, formed with a conical seat 19, for the reception of the needle point end 20 of a controlling valve 21.

With the construction described, it will be 60 understood that by merely removing the combined nut and valve 13, it is possible to simultaneously remove the supply tube 12, the valve parts and the burner parts connected with the tube 17. This forms a unit assembly having a minimum of joints between which

the fluid can escape, and at the same time materially decreases the overall dimensions of the parts, enabling the height of the furnace to be kept materially lower. If desired, however, the burner tube assembly hereinafter described in detail and comprising the tube 17 may be bodily removed independently of the unit valve body, thereby permitting removal or replacement of the individual parts at will.

In Figure 6, there is illustrated a modified method of constructing the reservoir and of securing the bushing therein. In this figure, parts corresponding to parts already described are designated by the same reference characters having a prime affixed thereto. The main body 2⁷ of the reservoir has a depression adapted to receive the bushing 14⁷ whereby the top of the bushing may be in, below or only slightly above the plane of the top wall of the reservoir. In this manner, the unit valve body 13⁷ is more compactly assembled and the overall height of the furnace correspondingly decreased.

The burner tube 17 may be of any desired shape, but preferably extends upwardly into a burner head 22, within which it is formed with a horizontally extending portion 23, the other end of which terminates in a downwardly and upwardly extending burner 24. With this construction, the burner tube is subjected within the burner head to the heat of the flame issuing from the burner, whereby the desired heat for vaporizing the liquid fuel is obtained.

In order to start burners of this character, it is necessary to provide suitable means by which the burner head and at least a portion of the burner tube may be initially heated. For this purpose, we provide the body 13 with a shoulder 25 and a second shoulder 26. Around the shoulder 26 is secured a cup 27, which is preferably brazed in position and is of sufficient depth throughout the main body thereof to shield the flame intermediate the burner and the burner head. At one side, however, this cup is provided with a slot 28, determining the maximum effective depth of the cup, so far as its liquid holding capacity is concerned, and also to provide cleaning access to the burner or jet block. In use, workmen ordinarily fill these cups completely full and then light the fuel therein. After the fuel starts to boil and expand, a considerable portion may be forced or splashed outwardly, and unless caught or deflected in some manner, would reach the top of the reservoir, where it would burn and produce the objectionable temperature conditions above set forth. To obviate this, a secondary shield 29 is secured in position, as by brazing, around the shoulder 25. The shield 29 may be of a shape as illustrated in Figure 3, to give the maximum protection within the guard without interfering with the swinging movement

thereof. In operation, this shield 29 will receive all surplus fuel or droppings and effectively protect the reservoir. At the same time, it protects the reservoir from downwardly radiated heat, this, combined with the cooling action obtained by circulating air over the top of the reservoir by means of openings 30, effectively cooling the reservoir and preventing damage thereto.

10 For obtaining the necessary pressure within the reservoir to insure the feed of fuel, there is provided a pump cylinder 31, which may be generally of the construction illustrated in the patent to J. E. Flitcroft, No. 15 1,030,465 of June 25, 1912. Within this barrel is mounted a piston rod 32, the upper end of which is preferably shaped to provide an operating handle 33, capable of being conveniently gripped by an operator. Such advantages may be obtained by extending one 20 end of the handle, as clearly shown in Figure 1, to permit two or more fingers to be passed thereunder. The top of the handle may be formed with a locking depression 34, 25 adapted to receive a coiled spring 35, carried by a clevis 36, mounted on studs 37 projecting laterally from the bushing 38, which carries the pump barrel. These studs preferably have shoulders or heads 37' so positioned and 30 shaped as to preclude the possibility of accidental loss of the clevis or removal of the same from the studs, with a consequent loss of the use thereof as a supplemental sealing or safety device.

35 Heretofore, as illustrated in the patent referred to, it has been customary to provide such bushings with a single nut for securing the barrel in position and guiding the piston rod. In accordance with the present invention, the bushing is provided not only with a main nut 40, but also with a secondary nut 41, threaded thereinto and removable independently thereof. This secondary nut is extremely important from an operating 45 standpoint, for the reason that it is removable independently of the barrel or of the nut and may be replaced at will when worn by the operation of the piston rod to insure the maintenance of a tight joint at all times. 50 Also it permits removal or partial withdrawal of the pump piston independently of the barrel, whereby the pump washer may be lubricated to preserve the same and improve its efficiency or to replace the same.

55 The hinged guard 6 is shaped to provide an opening 42 for the reception of a pump and its associated parts and, where the valve 21 extends horizontally, with a slot 43 for its reception. It will be apparent, however, that 60 the valve may extend laterally at any desired angle, whereby the size of the slot may be effectually decreased. Where the filler plug 44 is positioned as illustrated in Figure 2, the guard will also be shaped to accommodate 65 such plug.

The filler plug 44, the combined unit valve assembly 13 or 13', and the bushing 38 may all be constructed to receive packing washers W. These washers while they may be of any desired construction and material, are 70 preferably formed of fibre, it having been found that fibre cracks under predetermined temperature conditions, thereby effectively releasing abnormal and dangerous pressure conditions from within the reservoir. This 75 forms a desirable safety feature in connection with the furnace operation.

In order to permit lighting a burner without the necessity of swinging the guard about its pivotal mounting, the guard may carry a 80 closure 45, which may be moved into and out of operative position at will, by any suitable mounting thereof. In Figure 7, the closure 45' is shown as being within the guard 6', whereby it is effectively protected against 85 distortion and consequent binding, although it will be obvious that such a location is not essential. Also secured to this guard in any desired manner is a suitable bail 46, by means of which the furnace may be readily transported from place to place as required. 90

With apparatus of this character, it is desirable to take all possible precaution against the loss of vapor or fuel from the reservoir. In some cases, therefore, it may be 95 advantageous to so position the ports 15' and 16', as shown in Figure 6, that the end 20' of the valve 21' will be effective for sealing both ports. With such a construction, even if the seal effected with one of the ports should be defective, the seal established with the other port will be effective. 100

Certain advantages of the present invention arise from the provision of a furnace of the general character contemplated herein, having a guard cooperating with the reservoir in such manner as not to tend to collect foreign matter on the reservoir, and at the same time movable to inoperative position to facilitate access to certain of the operating 105 parts of the furnace. 110

Other advantages of the invention arise from the provision in a furnace as set forth, of a shield so mounted as to permit movement of the guard to inoperative position and at the same time serving to protect the reservoir from burning fuel, droppings from the pot or material resting on the top plate or other foreign matter, either alone or in combination with openings, insuring an air circulation between the shield and the reservoir whereby heat is carried away from the furnace and the reservoir. 115

Still further advantages of the invention arise from the provision of an improved burner mounting embodying a unit valve body adapted to permit either independent removal of the burner parts or simultaneous removal of the burner, priming cap, shield, valve body and fuel-feeding tube. 120 125 130

Still further advantages of the invention arise from the provision of the improved pump mounting, and from the utilization of a construction such that washers may be utilized in such manner as to constitute means for automatically relieving pressure conditions within the reservoir when the same becomes subjected to increased temperature beyond a predetermined minimum from any source whatsoever.

Additional advantages arise from the construction of the pump and pump handle, whereby easier operation thereof is obtained, as well as from the mounting of the holding clevis in such manner that accidental loss or removal thereof is impossible.

We claim:

1. In a furnace, a fuel reservoir, a burner supplied thereby, a guard having a connection with said reservoir permitting movement of the guard to operative and inoperative position relative to said burner, a drip cup for said burner, and a shield cooperating with said burner and drip cup and positioned within the guard when the same is in operative position to protect said reservoir, substantially as described.

2. In a furnace, a fuel reservoir, a burner supplied thereby, a guard pivotally secured to said reservoir and permitting swinging movement of the same into and out of operative position relative to said burner, a drip cup for said burner, and a shield cooperating with said burner and drip cup and positioned within the guard when the same is in operative position to protect said reservoir, substantially as described.

3. In a furnace, a fuel reservoir, a burner carried by said reservoir, a guard pivotally carried by said reservoir whereby the same may be swung into and out of operative position with respect to said burner, said guard in closed position abutting against the top of said reservoir, and a shield cooperating with said burner and shaped to permit swinging movement of said guard, substantially as described.

4. In a furnace, a fuel reservoir, a burner supplied by fuel from said reservoir, a combined temperature and liquid collecting shield cooperating with said burner and mounted entirely in spaced relation to said reservoir, and a guard for said burner having an open bottom end adapted to be closed by said reservoir, said guard being provided with an opening to permit the circulation of air between said shield and said reservoir, substantially as described.

5. In a furnace, a fuel reservoir, a burner supplied by fuel from said reservoir, priming means for initially obtaining the desired operating temperature for said burner, and a combined temperature and liquid collecting shield intermediate said priming means and said reservoir and spaced entirely from said

reservoir and priming means to shield the same, substantially as described.

6. In a furnace, a fuel reservoir, a burner supplied by fuel from said reservoir, priming means for initially obtaining the desired operating temperature for said burner, a shield intermediate said priming means and said reservoir and spaced from said reservoir to shield the same, and a guard cooperating with said burner and constructed to insure the circulation of air between said shield and the reservoir, substantially as described.

7. In a furnace, a fuel reservoir, a burner, a guard, a top plate carried entirely by said guard, a shield intermediate said burner and reservoir and spaced therefrom, said guard having an open lower end adapted to move over said shield and normally abut directly against said reservoir and be closed thereby, and a connection between said reservoir and guard permitting the guard to be swung at will to inoperative position to permit access to said burner and to the top of said reservoir.

8. In a furnace, a fuel reservoir, a burner carried by said reservoir, a guard pivotally carried by said reservoir whereby the same may be swung into and out of operative position with respect to said burner, said guard in closed position abutting directly against the top of said reservoir, and a shield spaced from said reservoir and burner and cooperating with said burner, said shield being shaped to permit swinging movement of the guard over the same.

In testimony whereof we have hereunto set our hands.

HARRY E. LEETY.
